DISPLAY RACK FOR MAGAZINES, BROCHURES
AND THE LIKE

Leif Johan Elvestad, Skogfaret 17C, Haslum, Norway

Filed Aug. 13, 1963, Ser. No. 76,198

Term of patent 14 years

Claims priority, application Norway, Apr. 30, 1963,
45,378

(Cl. D80—10)

FIG. 1

FIG. 3

FIG. 1 is a front perspective view of the display rack for magazines, brochures and the like showing my new design;

FIG. 2 is a side elevational view thereof; and

FIG. 3 is a top plan view thereof.

I claim:

The ornamental design for a display rack for magazines, brochures and the like, as shown.
